UNITED STATES PATENT OFFICE.

ROBERT J. SHEEHY, OF NEW YORK, N. Y.

PRINTING-TELEGRAPH.

SPECIFICATION forming part of Letters Patent No. 325,702, dated September 8, 1885.

Application filed April 10, 1883. (No model.)

To all whom it may concern:

Be it known that I, ROBERT J. SHEEHY, a citizen of the United States, and a resident of New York city, in the county and State of New York, have invented certain new and useful Improvements in Electrical Type-Writers or Printing-Machines, of which the following is a specification.

My invention relates to certain improvements in the construction and organization of apparatus designed to be operated either for printing words and sentences, character by character, for telegraphically transmitting communications, or for recording communications so transmitted.

The general object of the invention is to provide efficient apparatus for subserving the requirements of the ordinary type-writer employed for business purposes and a printing-telegraph instrument for intercommunication.

The invention consists in organizing the following systems of apparatus, and in combining in one complete instrument all or any of the same, as required for particular purposes. A longitudinally-movable carriage, upon which is placed the paper which is to receive the impressions, is placed at the back of the instrument. In front of the same is placed an annular series of type or a type-cylinder, which are successively brought, by the rotations of a supporting-shaft, into position to have their characters imprinted upon the paper. This shaft, and thus the type-cylinder, is revolved by means of an electro-magnetic motor before the paper thus presented.

For the purpose of determining the position in which the type-cylinder shall be arrested to permit the impression of a particular type on the receiving-instrument, an escapement device is applied to the motor, which device is actuated by the successive impulses traversing the circuit to permit the revolution of the shaft, but which acts, under the influence of a prolonged electric current, to arrest the movement of the same. Such a prolonged current is transmitted through the coils of the escapement device, through the instrumentality of a series of keys corresponding with the characters borne by the type, and arranged, when depressed, to complete the necessary circuit-connections for establishing such a current at the moment the corresponding type is pre-

sented to the paper. The same impulse acts to complete the connections of an electric circuit, in which is included a printing-magnet, 55 which magnet actuates the one or the other of two type-levers respectively corresponding with two series of type, thereby causing one or the other of two types simultaneously presented to the paper to be imprinted upon the same. 60 After an impression has been made by any of the type, the paper-carriage is caused to advance through the space occupied by a single impression, through the agency of a pawl operated by the lever of the printing-magnet, 65 and acting upon a pinion applied to a rack-bar carried upon the paper-carriage. Devices for returning the carriage to the proper position for commencing a line, and for moving the paper vertically with reference to the type 70 at any point in the excursion of the carriage, are also provided, and also means for automatically transmitting to a similar instrument electric impulses of the proper frequency and duration for actuating that instrument correlatively with the transmitting-instrument. 75

The invention also comprises certain details of construction and organization of apparatus, hereinafter fully set forth.

In the accompanying drawings, which illustrate my invention, Figure 1 is a front elevation of an instrument embodying the features of my invention, and Fig. 2 is a vertical cross-section of the same. Fig. 3 is a plan view of the instrument. Fig. 4 is a plan view taken 85 on a lower plane than Fig. 3, showing particularly the construction of the motor. Figs. 5, 6, and 7 illustrate certain details of construction, and Fig. 8 is a theoretical diagram showing the organization of the electric circuits. 90

Referring to the drawings, A represents a suitable base, and A' a frame for supporting the various parts of the instrument. At the upper and rear portion of the instrument is 95 placed a paper-carrier, B, laterally movable upon two supporting-rockers or wheel-segments, B' and B'', the hubs b' and b'' of which respectively surround two transverse axes, b³ and b⁴, at the respective extremities of the 100 carriage. The peripheries b⁵ and b⁶ of the wheel-segments B' and B'' are preferably in the form of segments of circles, and provided with teeth which mesh into corresponding

teeth formed in the surface of suitable horizontal grooved tracks b^7 , placed upon the base A of the instrument. These wheels permit the carriage to be moved laterally in either direction and in a constant horizontal plane.

The carriage B is constructed as follows: A paper-carrying roller, C, is supported at its respective extremities in suitable bearings, c^1 and c^2 , formed in two arms, C' and C'', which arms form a portion of the frame of the carriage. A second roll, C³, is likewise supported at either extremity in bearings formed in the arms C' and C'', and serves to feed the paper to the type. A friction-roller, C⁴, is supported above the roller C³ upon arms c^{10} , pivoted to the arms C' and C'', and is pressed by means of suitable springs, c^{11} , against the feeding-roll C³. A paper-guide, C⁵, is provided for bringing the paper into the proper position for receiving the impressions from the type. This guide consists of a friction-roller, c⁵, and two parallel rods, c^8 and c^9 . The friction-roller c⁵ extends parallel with the rolls C and C', and is supported at each end in arms c^6 and c^7 , respectively secured to the arms C' and C''. The rod c^8 is supported by the arms c^6 and c^7 , and is placed in front of the roller c⁵, and at a sufficient distance therefrom to allow the paper to pass freely between the same. The rod c^9 corresponds to the rod c^8 , and is similarly supported in arms c^{12} and c^{13} , but at a sufficient distance above the same to permit the type to be pressed against the paper between the two. An arm, D, carrying at its extremity a platen, d, extends from the central and rear portion of frame A' toward the type. This platen is preferably adjustably affixed to the arm D, and extends above the roller c⁵ and into proximity to the paper which is passing through the guide C⁵.

Extending vertically from the lower portion of the frame A' of the instrument is a shaft, E, carrying at its upper extremity a cylindrical support, F, in which are placed two annular series of movable type, F' and F''. The shaft E has near its lower extremity a bearing, e, formed in a transverse portion, a', of the frame A', and near its center a second bearing in a plate, a'', of the frame A'.

The type-cylinder F consists of a horizontal disk, F³, adjustably affixed to the shaft E by means of a set-screw, f, extending through a collar, f', formed upon its upper side and surrounding the shaft, which disk is secured to a parallel annular plate, F⁴, by means of two concentric rings, f³ and f⁴, fitting between annular lugs f⁵, formed upon the confronting surfaces of the plates F³ and F⁴.

For convenience in construction the two rings f³ and f⁴ are preferably constructed in one piece with a horizontal annular plate, f², which is secured to the disk F³ by screws or pins f⁶. The plate F⁴ is fastened to the rings f³ and f⁴ by screws or pins f⁷, extending through the lugs f⁵, and similar screws may be applied

to the upper peripheries of the rings, as shown at f⁸. Two ranges of apertures, F⁵ and F⁶, are formed in each of the concentric rings f³ and f⁴, through which extend the shanks f⁹ of the two series of type F' and F'', respectively. These apertures are preferably formed by cutting radial slots through the plate f² and into the rings f³ and f⁴, somewhat deeper than the depth of the type shanks. Similar openings or slots are cut from the lower edges of the rings upward for the lower series of type. There is left thus a skeleton frame formed about the continuous portion of the two rings not cut away. When the disk F³ and annular plate F⁴ are applied to the same, the openings at the top and bottom of the slots will be closed thereby. The number of apertures in the two rings are equal, and the apertures in the one ring are situated in the same radial lines as the corresponding apertures in the other. The shape of the apertures is preferably rectangular, and the size and form of each type-shank f⁹ is such that it may be readily moved backward and forward therein, but may not be turned axially. Surrounding the portion of each of the type-shanks between the two concentric rings f³ and f⁴ is a coil-spring, f¹⁰, the outer coil of which, f¹¹, presses against the outer ring, f³, while its inner end is secured to a pin in the type-shank, as shown at f¹². The function of this spring is to normally hold the type toward the center of the type-cylinder with the inner extremity of the shank projecting slightly beyond the inner ring, f⁴. The pin f¹² also serves to prevent the type from being pressed too far toward the center of the cylinder.

The faces of the type in the series F' and F'' are configured to represent the various characters which it may be desired to imprint upon the paper. The type in the lower series, for instance, may be employed for representing the numerals and other characters, while those in the upper series represent letters of the alphabet.

The next feature of the invention to be described is that involving the device employed for rotating the type-cylinder. This device consists of an electro-magnetic motor, G, adapted to rotate a shaft, H, which is parallel with and geared to the type shaft E. The motor G comprises four electro-magnets, G', G², G³, and G⁴, through each of which, in recurring succession, an electric current is transmitted by the action of an automatic circuit-closing device, I. The circuit-controlling device I consists of four contact-springs, i', i², i³, and i⁴, carried upon the supporting-plate i'. The springs i are electrically connected with each other and with a conductor, 27, which in turn is electrically connected with one pole of a battery, in a manner hereinafter described. The springs i are preferably arranged in pairs, one pair, i' and i², extending directly over each other upon one side of the shaft H, and the other pair, i³ and i⁴, at opposite points upon the other side of the same shaft. The portion of the

shaft H extending between the springs i carries two vertical cams, i^1 and i^2 , at right angles to each other, and arranged to impinge against the springs and bend them outward in recurring succession. The four contact-springs i^1 , i^2 , i^3 , and i^4 are thus caused by the motion of the shaft to respectively make successive contacts with corresponding adjustable contact-points j^1 , j^2 , j^3 , and j^4 , which are insulated from the supporting-plate i^5 , thereby continuing the electric circuit from the conductor 27 successively through the four conductors 10, 11, 12, and 13, respectively, uniting the contact-points j with the electro-magnets G' , G^2 , G^3 , and G^4 . The opposite terminals of the coils of these magnets are all united with a conductor, 14. The electro-magnets G , through which the electric circuits are thus closed, are respectively provided with armatures g^1 , g^2 , g^3 , and g^4 . These armatures are arranged in pairs, the armatures g^1 and g^3 being mounted upon opposite extremities of an armature-lever, g^5 , which is secured at its center to an axis or trunnion, g^6 , pivoted in the frame A'. The armatures g^2 and g^4 are in like manner carried upon a lever, g^6 , supported upon an axis, g^8 . Two arms or levers, g^9 and g^{10} , are respectively rigidly attached to the axes g^7 and g^8 , and extend toward and past each other at an angle preferably of about ninety degrees. The two arms are, however, in different planes, and thus independent of each other. Two links, g^{11} and g^{12} , respectively, unite the extremities of the arms g^9 and g^{10} with a crank, h , constituting a part of the shaft H, in such a manner that the backward and forward movements or oscillations of the arms g^9 and g^{10} will communicate a rotation to the shaft H.

The operation of the motor thus organized is, briefly, as follows: A circuit being closed through the electro-magnet G^3 , the armature g^3 is drawn toward the magnet and the arm g^9 impelled in the direction indicated by the arrow x' , thereby revolving the shaft H through one-quarter of a complete revolution. The circuit-controller I thereupon acts to close the circuit through the electro-magnet G^2 . The armature g^2 will then be attracted, and the arm g^{10} will be actuated in the direction of the arrow x^2 , and the shaft will be turned another quarter of a revolution in the same direction. The circuit being next closed through the electro-magnets G' and G^4 in succession, the arms g^9 and g^{10} will be actuated in the direction opposite to that indicated by the arrows x' and x^2 , and the shaft H will thereby be turned the remaining half of a complete revolution. This operation will be repeated so long as the circuit through the conductor 27 remains completed. The motion thus imparted to the shaft H is communicated to the type-shaft E through a pinion and gear-wheel, H', the relative sizes of which may be varied as found desirable for the purpose of obtaining the required rapidity of rotation on the part of the type-cylinder. It may here be observed that in certain instances it may be found desirable to substi-

tute for the electro-magnetic motor a mechanical motor of any suitable and well-known construction for driving the shaft E.

The apparatus for controlling the movements of the type-cylinder and determining the position in which it shall be arrested comprises a pole-changing device, N, for actuating an escapement mechanism applied to the shaft H, and a series of keys, K, for arresting the movement of the motor when the type-cylinder has reached a predetermined position—that is, the position in which the type corresponding with the particular key employed is in position to be actuated. The pole-changer N, which, it may be observed, is employed only in an instrument designed to be used as a transmitter, consists of two pairs of insulated contact-springs, n^1 and n^3 and n^2 and n^4 , placed upon opposite sides of the lower extremity of the shaft H. These pairs of springs are respectively carried upon two standards, n^5 and n^6 , extending from a base, n^7 , which base is secured to the frame A', but insulated therefrom. Each contact-spring n is provided with an adjustable contact-point, as shown at o^1 , o^2 , o^3 , and o^4 . These contact-points are carried in two insulated standards, o^5 and o^6 , similar to the standards n^5 and n^6 . One pair of contact-springs, n^2 and n^4 , are electrically connected by a conductor, 7, through the coils of an electro-magnet, M, and, in a manner hereinafter described, with the conductor 8. The remaining pair of springs, n^1 and n^3 , are connected by a conductor, 15, with the earth or with the return-wire. The contact-springs n are normally held, by their own resilience, away from their respective contact-points o , but they are periodically placed in contact therewith during the revolutions of the shaft H by means of two double-faced cams, h^1 and h^2 , carried upon the portion of the shaft H extending between the springs. The cams h^1 and h^2 preferably consist of lateral enlargements of insulating material formed upon a sleeve with their axial planes crossing each other at right angles, and the sleeve is secured in position upon the shaft H by means of a set-screw. When the shaft H is revolved by the action of the motor G, the lug h^1 acts first to press the springs n^1 and n^3 against their respective contact-points o^1 and o^3 , and in its next quarter-revolution the lug h^2 acts to compress the springs n^2 and n^4 against the contacts o^2 and o^4 , respectively. In this manner the circuit of the battery O will be closed first from its positive pole through the conductor 1, contact-point o^2 , spring n^2 , conductors 7, 8, and 14, in a manner to be described, and from the negative pole through the conductor 2, and thence through the contact-spring n^1 , contact-stop o^1 , and conductor 15 with the earth. The continued revolution of the shaft H will cause the cam h^1 to be carried away from the springs n^1 and n^3 , while the cam h^2 acts to place the springs n^3 and n^4 in contact with the stops o^3 and o^4 , respectively, thereby closing the circuit from the positive pole of the battery O through the conductor 1, stop o^1 , and spring n^3 , and

the conductor 15 with the earth. The negative pole of the battery O is simultaneously connected with the stop o^4 , spring n^4 , and conductor 7, and thence through the conductors 8 and 14 to line. In this manner alternate positive and negative impulses are transmitted through the coils of the electro-magnet M. The successive changes in magnetization thus established act upon a polarized armature, m^3 , supported upon a suitable vertical axis, m^4 , impelling it toward its opposite poles m' and m^2 alternately.

Mounted upon the axis m^4 of the polarized armature m^3 is an arm, m^5 , carrying an anchor-escapement, m^6 , whose detents engage the teeth of a wheel, m^7 , mounted upon the shaft H. The vibrations, therefore, of the armature m^3 , occasioned by the rotation of the shaft H, permit the type-cylinder to be revolved in a well-known manner. It will become evident thus, that as there are but four reversals of current occasioned by the pole-changer N during each complete revolution of the shaft H, there should be but four teeth upon the periphery of the wheel m^7 . If, however, for any reason it is desired to vary the number of such reversals relative to the revolution of the shaft H, the number of escapement-teeth should be varied correspondingly. The wheel m^7 is preferably mounted upon a sleeve, m^9 , which loosely surrounds the shaft H, but which is united therewith by means of a coil-spring, m^8 , one end of which is fixed to the sleeve and the other to the shaft. A pin, m^{10} , extending through a slot, m^{11} , formed in the sleeve, permits a slight revolution on the part of the wheel m^7 independently of the shaft H. This movement, however, is preferably limited to the fraction of a revolution of the wheel m^7 required to revolve the type-cylinder through an arc equal to about one-quarter or one-half of the arc subtended by a single type. This construction is adopted for the purpose of preventing a too-sudden arrest of the motion of the mechanism by the action of the escapement when the printing is to be effected.

For the purpose of actuating the printing mechanism it is necessary, first, to arrest the motion of the shaft H at the proper point for bringing the required type in position to make its impression upon the paper, and, second, to transfer the circuit through an electro-magnet whose function it is to effect the impression. The former of these ends is attained by means of an electro-magnet, M^2 , situated in a local circuit, which circuit includes the keys K, segmental ring L, and interrupter X, hereinafter described. This electro-magnet is vitalized by closing any one of the keys in a manner hereinafter explained. The function of the electro-magnet M^2 is to arrest the movement of the shaft H, and thus that of the wheel m^7 when it is vitalized. The electro-magnet M^2 is for this purpose provided with an armature, h^7 , carried upon a trunnion, h^8 . This armature normally rests against a

back contact-stop, h^9 . The armature is electrically connected by a conductor, 26, with one pole of the local battery O^2 , while the stop h^9 is connected by a conductor, 27, through the circuit-controller I, thence through the electro-magnets G to the remaining pole of the battery by a conductor, 28. Extending from the trunnion h^8 is an arm, h^9 , carrying a pawl or detent, h^4 , for engaging the teeth of a wheel, h^5 , rigidly carried upon the shaft H. The armature h^7 is normally held by means of an adjustable spring, h^6 , away from the magnet M^2 , and the detent h^4 is at the same time maintained out of the path of the wheel h^5 . The armature h^7 , by moving toward the poles of the magnet, will place the detent h^4 in the path of the teeth of the wheel h^5 . The shaft H will thus be arrested in the position which it occupied at the moment of the completion of the local circuit therethrough. The type-cylinder, however, is not immediately arrested by the stopping of the shaft H, by reason of the yielding connection through the spring m^8 . The type-cylinder is thus made to advance after the arrest of the shaft H through a fraction of the space occupied by a single type, and it is arrested in that position by means of the escapement-arm m^5 , which arm is caused to engage the wheel m^7 and rigidly retain the same in the required position by reason of the polarized armature m^3 being held in a given position by a prolonged current which is transmitted through its electro-magnet when the shaft H is at rest. This same impulse acts upon a neutral armature applied to the same electro-magnet M to operate a switch for placing the printing-magnet in circuit, in a manner to be hereinafter described.

The device for completing the circuit of a section, O^3 , of the local battery O^2 through the electro-magnet M^2 comprises a bank of circuit-closing keys, K. The individual keys of the series K respectively correspond with the characters represented by the type carried in the cylinder F, already described. Each key consists of a pivoted circuit-closing lever, K' , and anvil K^2 . The levers K' are electrically connected with a conductor, 29, leading to one pole of the battery-section O^3 , and the anvils K^2 are respectively connected with the individual segments $l^1 l^2 l^3$, &c., of a segmental contact-ring, L, by means of conductors $k^1 k^2 k^3$, &c. The segments $l^1 l^2 l^3$, &c., thus connected are arranged in the same succession as the type f bearing the corresponding characters.

Secured to the type-shaft E is a contact-brush, L' , which rests upon the surface of the ring L, and is caused by the rotation of the shaft E to make successive contact with the segments l . This contact-brush is in electrical connection, through a second contact-brush, L^3 , pressing against the periphery of a contact-ring, L^4 , upon the shaft E, with the conductor 25, leading to the electro-magnet M^2 . The circuit is continued through a conductor, 30, and the interrupter X of the remaining

pole of the battery-section O^3 . If, therefore, any given key be depressed, a portion, O^3 , of the battery O^2 will be shunted through the coils of the electro-magnet immediately upon the contact of the brush L' with the particular segment l connected with the anvil of that key independently of the motor G . The shaft H and pole-changing device N being thus arrested, a prolonged current of either polarity will be sent from the battery O to the main line through the electro-magnet M . The polarized armature m^3 will thereupon be held toward one pole or the other of the magnet, and the type-shaft E in the receiving-instruments arrested with the particular type corresponding with the key depressed confronting the paper upon which the impression is to be made. The same impulse which thus arrests the type-cylinder acts upon a neutral armature, P' , supported in proximity to the poles of the electro-magnet M upon a horizontal pivoted lever, p' . This armature is normally held away from the poles of the magnet by a suitable retractile spring, p^2 , one end of which is applied to an arm, p^3 , secured to the arbor p^4 of the lever p' . The remaining end of this spring is fixed to a suitable tension-adjusting screw, p^8 , carried upon a bracket, Q' . The rapid succession of positive and negative impulses transmitted through the electro-magnet M is not of sufficient duration to draw the armature P' into proximity to its poles against the tension of the spring p^2 , and it therefore normally rests against an adjustable back contact-stop, p^5 . When, however, a prolonged impulse is caused to traverse the coils of this magnet, as hereinbefore described, the armature P' will respond to the consequent magnetization and be drawn forward until the arm p^3 rests against an adjustable limiting-stop, p^6 , carried in a suitable support, p^7 . The arm p^3 extends between two insulated pivoted switch-arms, q' and q^2 , carried upon the bracket Q' , which is secured to and preferably insulated from the frame A' . The arms q' and q^2 are respectively provided with adjustable contact-points q^3 and q^4 , which are designed to make electrical connections with an interposed stationary arm, q^5 , toward which they are impelled by a suitable spring, q^6 , acting to draw the two arms q' and q^2 toward each other. When the armature P' is in its backward position, the arm p^3 acts, by pressing against the extremity of the switch-arm q' , to retain the contact-point q^3 away from the intermediate arm, q^5 . The switch-arm q^2 , however, is at the same time drawn toward the arm q^5 , and its contact-point q^4 is in electrical connection therewith. When the armature P' is attracted into its forward position, the switch-arm q^2 will be forced away from the arm q^5 , and the contact-point q^3 will be placed in electrical connection therewith. The conductor 7 , leading from the electro-magnet M , is in electrical connection with the arm q^5 . The switch-arm q^2 is connected through the conductor 8 , which in the receiving-instrument is connect-

ed with the conductor 14 , leading from the motor G . The switch-arm q' is connected, through the conductors 17 , 18 , and 19 , and the coils of a printing-magnet, P^2 , with the conductor 14 . When, therefore, the motor has been arrested by action of the detent h^4 and the escapement-arm m^5 , and a prolonged impulse is transmitted through the coils of the electro-magnet M , the motor itself will cease to exert a propelling force on account of the interruption of the circuit therethrough by the action of the armature h^1 , and the circuit through the printing-magnet P^2 will be completed, and this last-named magnet will be vitalized.

The printing-magnet P^2 is provided with an armature, p^8 , carried upon a lever, p^9 , which lever is supported upon an arbor, p^{10} , having its bearings in a suitable bracket, p^{11} , secured to the frame A' . Secured to the arbor p^{10} is an arm, p^{12} , forming a right angle with the armature-lever p^9 , and extending behind a perpendicular T-shaped lever, r . The lever r is pivoted to a bracket, r' , secured to the frame A' , and is provided with an extension, r^2 , the function of which will be hereinafter pointed out. The arm p^{12} extends through a mortise, r^3 , formed within the lever r , and serves, when the electro-magnet P^2 is vitalized, to communicate a forward motion to that lever.

Upon the respective arms r^4 and r^5 of the T-shaped lever r are pivoted two pawls, r^8 and r^9 , which pawls are respectively constructed to engage the teeth of two ratchet-wheels, r^6 and r^7 . The pawls r^8 and r^9 are respectively pressed against the peripheries of these ratchet-wheels by coiled springs r^{10} , surrounding their respective supports and extending beneath the pawls. The ratchet-wheels r^6 and r^7 are respectively and independently mounted upon sleeves r^{11} and r^{12} , surrounding a common axis, r^{13} , which axis is carried upon suitable supports, r^{14} and r^{15} , secured to the frame A' .

Parallel with the axis r^{13} and similarly supported in two brackets, s' and s^2 , is an axis, s^3 , surrounding which are two sleeves, s^4 and s^5 , carrying levers s^6 and s^7 , respectively. The extremities of the levers s^6 and s^7 extend above the ratchet-wheels r^6 and r^7 , respectively, and are pressed against the same by coiled springs s^8 and s^9 , surrounding the axis s^3 , and having their respective ends attached to the axis-support and the corresponding sleeve in a well-known manner. The teeth of the ratchet-wheels r^6 and r^7 are preferably constructed to present beveled or tangential faces to the corresponding levers, s^6 and s^7 , while the other faces are perpendicular or radial as regards the centers of the wheels. The pawls r^8 and r^9 engage these teeth upon their perpendicular faces. When the arm p^{12} is thrown forward by the action of the armature-lever p^9 , one or the other of the ratchet-wheels r^6 or r^7 will be rotated, and the corresponding lever, s^6 or s^7 , will be first carried upward by the tooth upon which it rests, and then allowed to fall sud-

denly against the succeeding tooth. The device for determining which of the wheels r^6 or r^7 shall be thus actuated will be hereinafter described. The sleeve s^1 , which carries the lever s^6 , also carries an arm, R' , for actuating the particular type of the series F' which confronts the paper when the printing is to be effected, and the sleeve s^5 likewise carries an arm, R^2 , which is in like manner employed for actuating the type in the series F^2 . The arm R' carries at its upper extremity a projection or hammer, R^3 , which is normally held away from the type f by the action of the corresponding coiled spring, s^8 . When, however, the lever s^6 is elevated by the wheel r^6 , this hammer will be thrown against the projecting end of the shank of the particular type which is presented to the paper, and will cause it to be forced forward against the paper. A similar hammer, R^4 , is in like manner carried upon the extremity of the arm R^2 , and is caused to actuate the particular type in the series F^2 in the path of the same when the wheel r^8 is revolved.

The device for determining which ratchet-wheel, r^6 or r^7 , shall be actuated, and consequently whether an impression shall be made by a type in the series F' or F^2 , consists of a movable wedge-shaped block, t' , designed to be thrown between the teeth of one or the other of the two ratchet-wheels and the corresponding pawl, and to thereby prevent that pawl from engaging the same. The block t' is carried upon an arm, t^6 , extending from a rock-shaft, t^3 , between the two pawls r^8 and r^9 . The rock-shaft t^3 extends horizontally beneath the levers s^6 and s^7 , and is supported in suitable bearings formed in standards t^4 and t^5 . The remote extremity of this shaft carries a forked arm, t^{10} . The levers s^6 and s^7 are respectively provided with horizontal extensions t^6 and t^7 , a function of which is to force one or the other of two vertical rods or pins, t^8 or t^9 , against the prongs t^{11} and t^{12} , respectively, of the forked arm t^{10} , thereby turning the rock-shaft t^3 toward the right hand or toward the left, and causing the block t' to stand between the teeth of one or the other of the wheels r^7 or r^6 . The rods t^8 and t^9 are carried upon a disk, T' , adjustably affixed to the shaft E . The rods t^8 and t^9 extend through slotted sleeves t^{14} and t^{15} , respectively, and are prevented from turning axially by means of suitable pins, t^{16} , extending through the rods and projecting through the slots formed in the sleeves. They are, however, capable of a vertical movement, which is limited by the length of the slots through which the pins project. Suitable coil-springs, t^{17} , surrounding the upper portions of the rods normally sustain the same in their upward position, in a manner well understood. The lower extremities of the rods t^8 and t^9 are provided with arms t^{18} and t^{19} , respectively, which, when either rod is in the proper position to be engaged by its corresponding arm, t^6 or t^7 , will engage the corresponding prong, t^{11} or t^{12} ,

of the forked lever t^{10} . It is evident that as the disk T' is fixed to the shaft E , and therefore revolves with the cylinder F , at the moment either rod t^8 or t^9 is in position to be engaged by the corresponding extension, t^6 or t^7 , the type-cylinder will be in a predetermined position. In order, therefore, that the block t' may be actuated without printing, I prefer to construct the type-cylinder with blank spaces which will confront the paper at the instant the rod t^8 or t^9 is in position to be actuated.

The operation of this device is as follows: Considering the block t' to be placed between consecutive teeth in the wheel r^7 , as indicated in the drawings, the pawl r^9 will slide over the surface of the same when the lever p^{12} is actuated, while the pawl r^8 will cause the wheel r^6 to be driven forward and a type in the series F' to be impressed. If, now, it is desired to print from the series F^2 , the shaft E is permitted to revolve until the rod t^8 is beneath the arm t^6 , and then the printing-magnet is automatically vitalized in the same manner as if a character were to be printed, and the wheel r^6 is again impelled forward by its pawl r^8 . The extension t^6 thereupon forces the extension t^{18} of the rod t^8 against the prong t^{11} of the forked arm t^{10} , thereby causing the shaft t^3 to be turned toward the left hand, and the block t' to be transferred from its former position to a corresponding position relative to the wheel r^6 between the teeth of that wheel which succeeds the tooth engaged by the pawl r^8 . The subsequent movements of the pawl r^8 do not effect the movement of the wheel r^6 , but the wheel r^7 will be actuated by the pawl r^9 . The chuck t' may be transferred to its former position by means of the arm t^6 and pin t^6 in a manner precisely similar to that just described. When a character has been imprinted by a type from either series F' or F^2 , it is necessary that the carriage B should be so actuated that the paper will be in position for receiving the succeeding character. This end is accomplished through the agency of a hook-pawl, u' , pivoted upon the extremity of the armature-lever p^3 , and constructed to engage the successive teeth of a spur-wheel, u^2 . The wheel u^2 is carried upon an arbor, u^3 , mounted in the bearings u^4 and u^5 upon the frame A' , and extending beneath the rack-bar C^6 , before referred to. A pinion, u^6 , mounted upon the arbor u^3 , engages the teeth of this bar which are so proportioned that each time the pawl u' actuates the wheel u^2 the carriage B will be advanced the required distance. A suitable dog, u^7 , normally engages the teeth of the wheel u^2 and prevents a retrograde movement of the same. This dog, as also the hooked pawl u' , is provided with rear extensions, as shown at u^8 and u^9 , which extensions serve as counterpoises for causing them to engage the teeth of the wheel. For the purpose of releasing the wheel from the pawl and dog when it is

desired to return the carriage to the position for commencing a line, an electro-magnet, V', is mounted upon the frame A' and provided with an armature, v', and armature-lever v², pivoted at v³ and provided with a right-angled extension, v⁴. This extension passes beneath the rear extensions, u⁸ and u⁹, of the pawl and dog, and, when the armature is drawn toward its electro-magnet against the force of its 5 tactile spring u¹⁰, acts to raise the extensions, thereby releasing the wheel u². The carriage is then free to move back to its starting position in response to the force exerted by a weight, v⁵, attached thereto by a cord, v⁶, passing over a pulley, v⁷.

The device adopted for vitalizing the electro-magnet V' comprises a circuit-breaker, V², through which the connections of the conductors 17 and 18 are normally completed, 20 but which may be actuated in a manner similar to that adopted for operating the block t', to sever those connections, and to thereby cause the current to traverse the coils of the electro magnet V'. To this end a lever, v⁸, is pivoted to an insulated portion, v⁹, of the frame A', and extends into proximity to the circle described by a vertically-movable rod, v¹⁰, carried upon the disk T', and similar in general construction to the rods t⁴ and t⁶. 25 Upon the upper extremity of the rod v¹⁰ is carried a projection, v¹¹, which once in each revolution of the disk is brought above the extremity of the lever v⁸, and at the same time the rod itself is in position to be forced downward by the action of the lever s⁶. At the remote extremity of the arm v⁸ is carried a contact-point, v¹², which normally rests upon an insulated contact-stop, v¹³. Upon the keyboard is provided a key for arresting the type-shaft E at the proper point to bring the projection v¹¹ in position to engage the arm v⁸. From the arm v⁸ a conductor, 20, extends to one terminal of the coil of the electro-magnet V', while the remaining terminal of the same coil is 30 connected by a conductor, 21, with the contact-stop v¹³. The connections of the conductors 17 and 18, which are respectively united with the arm v⁸ and contact point v¹³, will thus be normally completed through the circuit-breaker v², and practically no current will traverse the 35 electro-magnet V'. If, however, the lever v⁸ be actuated through the instrumentality of the lever s⁶ and rod v¹⁰ in the manner indicated, this circuit will be interrupted and the entire current be forced to traverse the coils of the electro-magnet V'. The armature v' will thereupon be 40 actuated and the wheel u² released in the manner already described. The circuit through the electro-magnet M' is interrupted either by the opening of the key by means of which it was first caused to be vitalized, or through the 45 automatic action of the interrupting device X. The armature h¹, by falling away, both releases the clutch-wheel h² and again completes the 50 circuit of the motor. The shaft H is thus permitted to advance independently of the

clutch-wheel h², by reason of the spring m⁸, a sufficient distance to act through its cams to reverse the connections of the main-line battery. This change in the polarity causes the 55 armature m⁹ of the electro-magnet M to be actuated, and thus the wheel m⁷ will be released and the operation may be repeated.

For the purpose of avoiding the necessity of operating the key and electro-magnet V' for 60 returning the carriage to its starting-point when the carriage has reached the limit of its excursion toward the left hand, a mechanical device arranged to be automatically operated to release the pawl and dog is provided. This 65 device consists of a cam, y', carried upon a shaft, y², and extending beneath the rear extensions, u⁸ and u⁹. The shaft y² is supported from the frame A' in a suitable standard, y³, and normally rests in such a position that the 70 cam is out of the path of the extensions. A pin, y⁴, at one extremity of this shaft projects into the path of a stop, y⁵, fixed upon the frame of the carriage C in such a position as to be brought into contact therewith when the carriage 75 has reached the limit of its movement toward the left hand. The effect of the stop y⁵ coming into contact with the pin y⁴ is to turn the shaft y² in its bearings until the eccentricity of the cam has raised the extensions u⁸ and u⁹ sufficiently to release the wheel 80 u² from the corresponding pawl and dog. The carriage will thereupon automatically return to its starting-point. A second stop, y⁶, is carried upon the carriage C near its left-hand 85 extremity, which stop engages the pin y⁴ upon the side opposite from the stop y⁵ when the carriage has returned to the right-hand limit of its excursion, causing the shaft y² to be turned in the corresponding direction and the 90 extensions thereby released from the cam y'. The pawl and dog thereupon re-engage the wheel u².

For the purpose of revolving the drum C³ of the carriage to move the paper upward 95 when it is desired to print upon a new line, an electro-magnet, W, is placed near the starting-point of the carriage. This electro-magnet is provided with an armature, w', supported upon one arm of an angled lever, w². The lever 100 w² is pivoted to the frame A' at a point, w³, and carries at its remote extremity a spring-pawl, w⁴, which engages the teeth of a ratchet-wheel, w⁵, in such a manner that each downward movement of the armature w' in response to the magnetization of the electro-magnet W will cause the wheel to be advanced one tooth. The wheel w⁵ is loosely mounted upon a rectangular shaft, w⁶, constituting an 105 extension of the axis of the drum C³. The shaft w⁶ is thus permitted to slide freely through the wheel w⁵, but may not be turned without moving the wheel. The wheel itself is retained in its proper lateral position by means of an arm, w⁷, and a bracket, w⁸.

When it is desired to actuate the drum in the manner above described, the electro-mag-

- net W is vitalized by means of a current caused to traverse its coils through the instrumentality of a device, W², similar to that employed for vitalizing the electro-magnet V'. 5 This device consists of a lever, w⁸, carried upon the support v⁹, and provided with a contact-point, w¹², normally resting in contact with a circuit-closing stop, w¹⁴. The lever w⁸ extends beneath the disk T' and into proximity to a rod, w¹⁰, carried upon that disk. 10 The rod w¹⁰ is similar in construction to the rod v¹⁰, and carries at its lower extremity a projection, w¹³, which once in its revolution is brought above the extremity of the lever w⁸. 15 A key is provided for arresting the motion of the shaft E in the proper position for causing the lever s⁶ to strike the rod w¹⁰ and to thereby actuate the circuit-breaker in a manner precisely similar to that already described 20 with reference to the circuit-breaker V' for releasing the carriage. The conductor 18, leading from the circuit-breaker V', is connected with the arm w⁸, and the contact-point w¹⁴ is connected with the conductor 19. The arm w⁸ 25 and contact-point w¹⁴ are, moreover, respectively connected, through conductors 22 and 23, with the respective terminals of the coil of the electro-magnet W. The same current, therefore, which actuates the printing device 30 normally traverses the circuit-breaker W², and practically no current will traverse the coils of the electro-magnet W. When, however, the circuit-breaker W² is actuated in the manner indicated, the armature will be actuated and the drum revolved, as already described. 35 For the purpose of automatically and mechanically operating the drum-revolving mechanism when the carriage is returned to its starting-point, a beveled arm, w¹⁶, is secured to the end of the carriage adjacent to the electro-magnet W, and so placed relative to the armature w' of the same that it will, when the carriage is returned nearly to its 40 starting-point, pass above the armature and gradually press it toward the poles of the magnet. The wheel w⁵ and shaft w⁶ will thereupon be actuated in the same manner as if the electro-magnet had been vitalized. In rapid 45 transmission it is desirable that the operation of the motor should be continued immediately after the impression of any type has been effected. For this purpose the device X is employed for interrupting the current which is transmitted through the electro-magnet M² when any one of the keys K has been actuated, and immediately after effecting the impression upon the paper, or immediately after the actuation of any of the subsidiary devices through the agency of the levers s⁶ or s⁷. The conductor 30, leading from the electro-magnet M², is connected with an insulated contact-point, x⁶, carried upon the support r¹⁴ of the wheels r⁶ and r⁷. Above this 55 contact-point extends a circuit-closing arm, x⁷, carrying an adjustable contact-point, x⁸,

and pivoted to the support r¹⁴ at x⁴. The point x⁸ is electrically connected with the battery-section O³, and it normally rests upon the point x⁶. Secured to the circuit-closing arm 70 x⁷ is an arm, x⁵, extending into the paths of the teeth of both the ratchet-wheels r⁶ and r⁷. The adjustments of the various parts are such that when either of the ratchet-wheels r⁶ or r⁷ is impelled by its pawl, and a type of the corresponding series, F' or F², has been struck upon the paper, one of the teeth of the corresponding ratchet-wheel, r⁶ or r⁷, will, by passing beneath the arm x⁵, cause the contact-point x⁸ to be separated from the point x⁶. The circuit through the electro-magnet M² will thereby be interrupted and the armature h' will be released. The circuit through the motor G will thereby be re-established, and the shaft H will again be actuated. The prolonged current through the electro-magnet M will also be interrupted, and the arm p³ will return to its normal position, thereby substituting for the circuit through the printing-magnet the normal circuit through the conductor 9. 80 Should the same key which occasioned the operation of the printing mechanism remain depressed, the operation will be repeated when the shaft E has completed a revolution, and the brush L' again makes contact with the corresponding segment, l. 90

In describing the invention thus far the instrument has been viewed as a recording and transmitting instrument. As it is designed, however, to employ the same instrument as a receiver as well as a transmitter, the necessity of providing a device for correcting any inaccuracy in the positions of the series of type becomes apparent. The device which I propose to employ for this purpose consists 105 of an arm or stop, z', fixed to the shaft E of the type-support, into the path of which a rod, z², is automatically thrust each time the carriage is returned to the right-hand limit of its excursion for commencing a line. The rod z² extends through a support, z³, in which it is longitudinally movable, and is normally held out of the path of the arm z' by means of a coil-spring, z⁴, surrounding the rod and compressed between the support z³ and a pin, z⁵. 110 Upon the carriage B is carried a pivoted arm, z⁶, the extremity of which is beveled both upon its face and lower edge, and is adjusted to pass behind the rod z² and to press it forward into the path of the arm z' when the carriage 115 is at the extreme right-hand limit of its excursion. If the type-shaft be allowed to revolve when the rod z² is thus pressed forward, it will be arrested by the contact of the arm z' therewith. By arranging the arms z' in all the instruments in the same position relative to their type-wheels, they will all be arrested in the same position each time the carriages are 120 returned to the starting-point. For the purpose of moving the beveled arm z⁶ out of the path of the arresting-rod z², and allowing the latter 125 to be returned to its normal position when it 130

has accomplished its purpose of arresting the type-shaft, a bell-crank, z^1 , is provided for elevating the extremity of the rod z^2 through the agency of the printing-magnet. The bell-crank z^1 is supported in a suitable bracket, z^3 , from the frame A', and one arm extends beneath the beveled extremity of the arm z^6 . To the remaining arm of the bell-crank z^1 is pivoted one end of a link, z^9 . In the opposite 10 extremity of the link z^9 is a slot, z^{10} , through which projects a pin, z^{11} , carried upon an extension, r^2 , of the lever r , hereinbefore described. The pin z^{11} normally plays in the slot z^{10} without moving the link. When the carriage is 15 at the right-hand limit of its excursion, the lower beveled edge of the arm z^6 acts to depress the arm z^9 of the bell-crank, and thus moves the link z^9 in the direction of the arrow. The first movement of the lever r thereafter, 20 through the action of the printing-magnet P', actuates the link z^9 in the opposite direction, and elevates the arm of the bell-crank z^1 , which extends beneath the arm z^6 . If, therefore, the type-shaft has been arrested at its proper 25 point, the arm z^6 will be moved out of the path of the bell-crank by transferring a circuit through the printing-magnet. This may be accomplished by depressing a key in the same manner as if a character were to be 30 printed. There being no type confronting the paper, however, no impression will be made, but the carriage will be advanced one space.

When the instrument is to be employed as a receiver only, it is apparent that certain 35 portions of the mechanism employed in the transmitter may be omitted. Thus it is evident that in a receiver the keys K and the segmental ring L would be omitted, as also the pole-changing device N and electro-magnet M'. The incoming currents would then 40 be conducted directly to the polarized electro-magnet M through a switch, X', and through a switch, X², and conductor 31 (shown in dotted lines) to the motor G, as illustrated in Fig. 8. 45 When the instrument is employed as a receiver, its motor is to be actuated by currents traversing the switch X', conductors 7 and 8, switch X², and conductor 31. A suitable switch, X³, is employed for interrupting 50 the circuit of the local battery when used as a receiver.

Any suitable form of inking-roller may be 55 employed in connection with the type F for rendering the impressions upon the paper visible. I prefer, however, when it is practicable, to employ in lieu of the inking device chemically-prepared paper, which may be 60 acted upon by electric currents transmitted therethrough from a battery, Z², (shown in dotted lines in Fig. 2,) when any type is placed in contact therewith. The positive 65 and negative poles of this battery are respectively in electrical connection with the type F and the platen d. The platen is for this purpose of conducting material. The paper-carriage and the platen d are in this construc-

tion to be insulated from the remaining portions of the instrument. When any type is pressed against the paper, an electro-chemical action will be occasioned through the portion 70 of the surface of the paper which is touched by the conducting-face of the type, thus recording the form of the type-character.

I claim as my invention—

1. The combination, substantially as hereinbefore set forth, of an annular series of independently-movable type, a shaft upon which said series is supported, means for revolving and for arresting said shaft, a paper-carriage and means for moving said carriage laterally 80 before said series of type, means for causing the particular type which confronts said paper-carriage to be moved toward the same and to effect an impression upon a sheet of paper upon said carriage, means for withdrawing 85 the same after it has been thus actuated, means for advancing said carriage step by step after effecting such impression, means for moving said carriage in the opposite direction from any point in its excursion, and 90 means for feeding the paper upward a line-space at any time, and for arresting the series of type in a predetermined position relative to the paper-carriage when said carriage has returned to one limit of its excursion. 95

2. The combination, substantially as hereinbefore set forth, of an annular series of independently-movable type, means, substantially such as described, for causing said type to be successively presented to a paper sheet, means, 100 substantially such as described, for arresting said series of type with any desired type confronting said paper sheet, a lever for causing the particular type confronting said paper sheet to be imprinted thereon, a toothed wheel 105 for actuating said lever, an electro-magnet, its armature and armature-lever for actuating said toothed wheel, and means, substantially such as described, for vitalizing said electro-magnet when said type have been arrested. 110

3. The combination, substantially as hereinbefore set forth, of two annular series of independently-movable type, means, substantially such as described, for causing the type in each 115 of said series to be successively presented to a paper sheet, two levers—one for actuating the type in each of said series—two toothed wheels respectively applied to said levers, each arranged to cause the character represented by the particular type confronting the paper to 120 be imprinted upon the same, and means, substantially such as described, for actuating said wheels.

4. The combination, substantially as hereinbefore set forth, of two annular series of independently-movable type, means, substantially such as described, for revolving and for 125 arresting said series, two levers—one for actuating the type in each of said series—two toothed wheels respectively applied to said levers, each arranged so as to cause the type 130 confronting the paper to be imprinted thereon,

means, substantially such as described, for actuating said wheels, and means, substantially such as described, for preventing the movement of either of said wheels when the other is being actuated.

5. The combination, substantially as hereinbefore set forth, of a revolving shaft, a disk carried thereon, vertically-movable pins carried upon said disk, levers extending above said disk, and means, substantially such as described, for actuating said levers at will, a shaft extending beneath said disk, a movable wedge or block secured to one end of said shaft, and a forked arm secured to said shaft and arranged to be engaged by one or the other of said pins, and to thereby rock said shaft and to place said wedge in the path of one or the other of said wheels.

6. The combination, substantially as hereinbefore set forth, of two pawls, two toothed wheels respectively actuated by said pawls, and a movable block or wedge acting to prevent one or the other of said pawls from engaging the teeth of the corresponding wheel, and means, substantially such as described, for actuating said block or wedge.

7. The combination, substantially as hereinbefore set forth, of a longitudinally-movable paper-carriage, two segments of wheels upon which said carriage is supported in a constant horizontal plane, longitudinal racks, and teeth formed upon said wheels meshing with the teeth of said racks.

8. The combination, substantially as hereinbefore set forth, of a movable paper-carriage, two or more toothed segments of wheels upon which said carriage is supported in a constant horizontal plane, longitudinal racks upon which said segments of wheels rest, a force tending to advance said carriage, a rack-bar extending longitudinally upon said carriage, a pinion engaging said rack-bar, an electro-magnet, its armature and armature-lever acting through the instrumentality of said pinion and rack-bar to control the movements of said carriage in response to said force.

9. The combination, substantially as hereinbefore set forth, of a movable paper-carriage, two toothed segments of wheels for supporting said carriage, rack-bars with which said segments engage, an electro-magnet, its armature and armature-lever for imparting to said carriage a step-by-step motion in a given direction and in opposition to a force exerted in the opposite direction, means, substantially such as described, for retaining the carriage in its advanced position, and a second electro-magnet brought into action at will for releasing said carriage from said retaining and advancing devices.

10. The combination, substantially as hereinbefore set forth, of a movable paper-carriage, a weight or other device tending to impel said carriage in one direction, a pinion and rack-bar for advancing said carriage in opposition to said weight, a pawl and detent for control-

ling the position of said pinion, and a cam automatically operated by a stop carried upon said carriage at one extreme of its excursion, to release said pinion from said pawl and 70 detent, and a second stop arranged to operate said cam at the opposite extreme of its excursion, to allow said pawl and detent to again act upon said pinion.

11. The combination, substantially as hereinbefore set forth, with the paper-feeding roller of a longitudinally-movable paper-carriage, of an angular shaft extending therefrom, a toothed wheel loosely mounted upon said shaft, and means, substantially such as 80 described, for actuating said toothed wheel and thereby rotating said paper-feeding roller at any point in the excursion of said carriage.

12. The combination, substantially as hereinbefore set forth, of the annular series of 85 type, the supporting shaft, the disk carried on said shaft, the vertically-movable pins carried upon said disk, the electro-magnets, the shunt-levers for causing either of said electro-magnets to be vitalized through the 90 instrumentality of said pins, and means, substantially such as described, for actuating said pins.

13. The combination, substantially as hereinbefore set forth, of a series of type, one or 95 more levers for actuating the type of said series, the toothed wheels for actuating said levers, the pawls for revolving said wheels, a lever for actuating said pawls, and an electro-magnet and its armature for actuating the 100 last-named lever.

14. In an electrical type-writer or printing-instrument, the combination, substantially as described, of the series of independently-movable type, the electro-magnet for actuating same, the circuit-transferring device, and a second electro-magnet, its armature and armature-lever acting through the instrumentality of said circuit-transferrer to complete the circuit through the first-named electro-magnet.

15. The combination, substantially as hereinbefore set forth, of an electro-magnetic motor, a printing-magnet, an electro-magnet normally included in the circuit of said motor, and an armature applied thereto, means, substantially such as described, for arresting the movement of said motor in any required position, a circuit-transferring device operated by the movement of said armature when said motor is arrested to substitute for the circuit through said motor a circuit through said printing-magnet, and means, substantially such as described, for re-establishing the normal connections through said 120 motor after said printing-magnet has been vitalized.

16. The combination, substantially as hereinbefore set forth, of a motor-shaft, a pinion loosely mounted upon said shaft and having a 130 yielding connection therewith, an annular series of type, a shaft for supporting the same,

a mechanical connection between said supporting-shaft and pinion, a scape-wheel revolving with said pinion, and means, substantially such as described, for controlling and 5 arresting the movement of said scape-wheel.

17. The combination, substantially as hereinbefore set forth, of a series of type, a supporting-shaft for said type, an electro-magnetic motor, its shaft, a mechanical connection between said shafts, and a circuit-controller for said motor, consisting of a series of contact-springs, a series of contact-points respectively applied to said springs and electrically connected with the electro-magnets 15 comprised in said motor, and a series of cams carried upon said motor-shaft, whereby said springs are successively placed in contact with their respective contact-points.

18. The combination, substantially as hereinbefore set forth, of a paper-carriage, a series 20 of type, a revolving shaft upon which said type are supported, a pin or stop fixed upon said shaft, a movable pin normally held out of the path of said fixed pin, a wedge-shaped 25 arm carried upon said paper-carriage, and acting when said carriage is moved into a given position to force said movable pin into the path of said fixed pin or stop.

19. The combination, substantially as hereinbefore set forth, of a series of type, a revolving 30 shaft upon which said type are carried, a pin or stop fixed to said shaft, a movable pin normally held out of the path of said fixed pin or stop, a wedge-shaped arm, and means, 35 substantially such as described, for causing said arm to place said movable pin in the path of said fixed pin or stop, a series of levers, substantially such as described, for moving said wedge-shaped arm out of engagement 40 with said movable pin, and means, substantially such as described, for actuating said levers.

20. In a type-writer or printing-instrument, a revolving type-shaft, a pin or stop moving 45 with said shaft, a movable pin normally held out of the path of said stop, a paper-carriage, an arm or cam moving with said carriage, and acting, when said carriage is moved into a given position, to force said movable pin into 50 the path of said stop, and to thereby arrest the motion of said shaft in a predetermined position, and means, substantially such as described, for simultaneously moving said arm or cam out of engagement with said movable 55 pin and for moving said carriage out of said given position.

21. The combination, substantially as hereinbefore set forth, of a series of type, a motor, a motor-shaft, means, substantially such as 60 described, for automatically arresting the movement of said shaft in a predetermined position, a spring through which said motor-shaft acts to revolve said series of type, and means, substantially such as described, for 65 permitting said series of type to advance a predetermined distance after said motor-shaft

is arrested, and for retaining the same in a position dependent upon the position in which said shaft is arrested.

22. The combination, substantially as hereinbefore set forth, with a series of type and its supporting-shaft, of a revolving shaft, a toothed wheel rigidly mounted upon said revolving shaft, a detent automatically actuated for arresting the movement of said wheel 75 and revolving shaft, a scape-wheel loosely mounted upon said revolving shaft, means, substantially such as described, for limiting the independent revolution of said scape-wheel relative to said revolving shaft, mechanism for communicating the movement of said scape-wheel to said series of type, and an automatically-actuated escapement-arm engaging said scape-wheel.

23. The combination, substantially as hereinbefore set forth, of a battery, an electro-magnetic motor, means, substantially such as described, for transmitting electric currents through the electro-magnets of said motor in succession, an electro-magnet acting, when 90 vitalized, both to interrupt the circuit through said motor and to arrest its movement.

24. In a type-writer or printing-machine, a battery, a series of circuit-closing keys, a segmental ring having its respective conducting-segments electrically connected with the anvils of said keys, a revolving type-shaft, a contact-brush carried thereon and caused by its movements to be placed in connection with said conducting-segments in succession, whereby the circuit of said battery is completed through any one of said keys which is depressed when said brush makes contact with the corresponding conducting-segment, an electro-magnet included in the circuit thus completed, and acting, when vitalized, to arrest the movement of said shaft and contact-brush, a circuit-interrupter included in the circuit with said electro-magnet, and means, substantially such as described, for actuating said 110 interrupter.

25. The combination, substantially as hereinbefore set forth, of a battery, an electro-magnet included in the circuit of said battery, a series of keys, a segmental contact-ring having its conducting-segments respectively connected with said keys, a contact-brush acting to complete the circuit of said battery through any key which is depressed, the corresponding contact-segment and the electro-magnet, and a circuit-interrupter placed in said circuit and acting to automatically interrupt the same independently of the movement of said key.

26. The combination, substantially as hereinbefore set forth, of a motor-battery, an electro-magnetic motor actuated by currents from said battery, a series of keys, and devices, substantially such as described, co-operating with said keys to arrest the movement of said motor in any required position, a pole-changing 120 device actuated by the movements of said motor, a second battery having its circuit 125

completed through said pole-changing device, a series of type controlled by the movements of said motor and said pole-changing device, a printing-magnet for actuating any of said 5 type, and an electro-magnet acting to automatically place said printing-magnet in the circuit of said second battery when said motor is arrested.

In testimony whereof I have hereunto subscribed my name this 9th day of April, A. D. 10 1883.
